AUTOMATIC GAS STERILIZER

Leonard L. Melanson, Stow, Mass., assignor to
Amdek Corporation

Filed May 6, 1971, Ser. No. 141,074

Term of patent 14 years

Int. Cl. D24—02

U.S. Cl. D83—1

Fig. 1.

Fig. 2.

Fig. 3.

FIG. 1 is a perspective view of an automatic gas sterilizer, embodying my new design, showing the front, right side and top.

FIG. 2 is a perspective view thereof showing the back, left side and top, and

FIG. 3 is a top plan view of the sterilizer.

I claim:

The ornamental design for an automatic gas sterilizer, substantially as shown and described.
